UNITED STATES PATENT OFFICE.

ANTHONY ISKE AND ALBERT ISKE, OF LANCASTER, PENNSYLVANIA.

HEAT-ALARM.

SPECIFICATION forming part of Letters Patent No. 434,872, dated August 19, 1890.

Application filed March 22, 1890. Serial No. 344,945. (No model.)

To all whom it may concern:

Be it known that we, ANTHONY ISKE and ALBERT ISKE, citizens of the United States, residing at Lancaster, in the county of Lancaster and State of Pennsylvania, have invented certain new and useful Improvements in Fire-
Alarms and Heat-Indicators; and we do hereby declare the following to be a full, clear, and exact description of the invention, such as will enable others skilled in the art to which it appertains to make and use the same.

This invention is an improvement on the fire-alarm and heat-indicator which forms the subject-matter of Letters Patent No. 287,439, granted to Anthony Iske and Albert Iske, October 30, 1883. In said patent a pair of bulbs connected by a tube inclose a volatile liquid *in vacuo*, the connection being such that when heat affects the lower bulb the vaporization and expansion of a part of the liquid in said bulb will force the remainder of said liquid up through the connecting-tube into the upper bulb, which then descends and operates or releases the alarm.

The general principle of the present invention is the same; but it has for its object to increase the sensibility of the mechanism to the action of heat, to provide for adjustment, and to secure greater simplicity. These ends are attained by the construction and combination of devices hereinafter particularly set forth and shown.

In the accompanying drawings, Figure 1 represents a side elevation of the bulbs and the devices operated thereby, the front of the inclosing-casing being partly broken away. Fig. 2 represents a vertical section through the same from front to rear. Fig. 3 represents an external side elevation of the same, with connection running to a mechanical alarm, and also electric wires for closing or opening circuit through any ordinary electrical alarm; and Fig. 4 represents the bulbs and tube having a weight attached thereto instead of the retaining-spring.

A designates the upper bulb, and B the lower bulb, of our volatile-liquid heat-indicator. These are connected by a tube C, which descends at c so far into said lower bulb B that the expansion of the vapor will force the

liquid up through said tube into said upper bulb, which will then descend by gravity.

Heretofore we have pivoted the bulbs on a shaft crossing the tube C midway between them. To secure greater leverage for the weight of the upper bulb, we now extend the pivot-shaft D transversely through the casing from front to back on the line of the center of the lower bulb. These bulbs, though so called in accordance with former nomenclature, are preferably metal cylinders, as shown, so that the shaft passes through the center of the lower one from end to end. This removes the pivotal point of the bulbs and their tube considered as an integral system to the lowest part of said system, and a much slighter degree of heat will suffice to cause the tilting thereof than would otherwise be necessary. By varying the quality of the volatile liquid the sensitiveness to heat may be further increased or diminished, the device being not merely a fire-indicator, but a thermostat of every degree.

One end of the lower bulb B is provided with a plate b, having on it a stud b', against which bears a spring E, having a catch E' formed thereon. This suffices to hold the upper bulb A in its normal position so long as said bulb is empty; but a slight increase of weight in said bulb will cause it to overcome the resistance of said spring and catch and descend. The tube C has a lateral finger F rigid therewith. Upon this rests one arm of a bent lever G, which is essentially a bell-crank lever, although the said arm is much longer than the other arm, which is normally upright. This upright arm (marked g of said lever,) is jointed at its upper end to a slide G', working through a slot in the side wall of the inclosing-casing H and also through a slot i in a face-plate I, attached to the exterior of said side wall. The protruding end of this slide enters the bifurcated end J² of a normally-horizontal catch J. This catch is pivoted near its other end on said face-plate and has a rearwardly-extending stud j, which is normally in close proximity to a laterally-extending lip I' of said plate. A hook K on the pull-cord L of an alarm mechanism is caught under this stud j and held by lip I' 100

against slipping off the same. When the upper bulb A drops, the long arm of lever G falls with it, and the upright arm *g* of said lever is tilted back, so as to withdraw the slide G' and release the bifurcated end J² of catch J. This end J² then falls, and in consequence the stud *j* rises and releases the hook K, so that the alarm is free to sound. Any suitable alarm held in check by said cord 5 may be used; but we prefer a clock-work alarm, such as shown in Patent No. 348,675 and in our patent application, Serial No. 334,572, now pending. In this the cord L passes around a pulley M, which turns with the winding-arbor 10 M' of the mainspring N of a clock-work train O, operating in the usual manner a hammer P, which acts on a gong Q. When the cord L is drawn down, the spring is wound. When the cord is released, the spring operates the 15 clock-work and the alarm.

No further description is necessary, the mechanism being fully set forth in the patent above mentioned.

To enable an electric alarm to be operated 20 by these bulbs and attachments, we attach two binding-posts R and S to the side wall of the casing H. One of these R is in contact with the plate or bracket T, attached to the inner face of said side wall and extending inwardly 25 therefrom, to which plate or bracket the lever G is pivoted. The other binding-post S is connected by a wire U to a bent stop-bar V, on which the long end of lever G falls when the upper bulb A reaches its lower position. 30 From the said binding-posts the circuit-wires W W' extend to any burglar-alarm, (indicated at X,) *y* being the battery, *y'* the magnet, *y*² the armature, and *y*³ the bell.

Z designates an arm extending laterally 35 from the tube C above the lower bulb B, and *z* designates a screw arranged to turn through the side wall of said casing and come in contact with the end of said arm. According as said screw is turned in more or less far the 40 bulb A will be allowed to tilt more or less into an upright position, thus regulating the leverage of the upper bulb and consequently the sensitiveness of the device. The spring E, by its catch E', holds the said bulbs and 45 their connecting-tube, as stated, whatever the adjustment. Instead of spring E we may employ (see Fig. 4) a weight E² on the end of an arm E³, bent back of the center of the lower bulb. The casing H of course incloses and 50 supports the pivot-shaft D and the other operative parts of the heat-indicator support. As there is no especial novelty in its construction, there is no need to describe it more fully. 55 The dotted lines in Fig. 4 show the position of the bulbs, the tube, the arm E³ attached thereto, and the weight E² on said arm when the alarm is operated.

Having thus described our invention, what we claim as new, and desire to secure by Letters Patent, is—

1. A heat-indicator consisting of two bulbs and their connecting-tube inclosing volatile liquid *in vacuo*, the said bulbs and tube being pivoted on a line passing through the 65 lower bulb, substantially as set forth.

2. A heat-indicator consisting of two bulbs and a connecting-tube containing volatile liquid *in vacuo*, the whole being pivoted as an integral device, in combination with an 70 adjusting-screw for regulating the position of the same, and consequently regulating the leverage of the upper bulb, substantially as set forth.

3. A heat-indicator consisting of two bulbs 80 and a connecting-tube containing volatile liquid, the whole being pivoted as an integral device, in combination with a spring which is arranged to hold the upper bulb against descending while empty, substantially as set 85 forth.

4. A heat-indicator consisting of two bulbs and a connecting-tube containing volatile liquid *in vacuo*, the whole being pivoted as an integral device on an axis passing through 90 the lower bulb, and the said lower bulb being provided with a projecting stud, in combination with a spring having a catch to engage with said stud, substantially as set forth.

5. A heat-indicator consisting of two bulbs 95 and a connecting-tube containing volatile liquid *in vacuo*, the whole being pivoted as an integral device on an axis passing through the lower bulb, in combination with an alarm and necessary connections, for the purpose 100 set forth.

6. A heat-indicator consisting of two bulbs and a connecting-tube containing volatile liquid *in vacuo*, the whole being pivoted as an integral device, in combination with a lever 105 supported by the upper part of said heat-indicator and descending therewith, a slide attached to said lever, a catch supported by said slide, and the pull-cord of an alarm set free by the withdrawal of said slide from 110 said catch, substantially as set forth.

7. A pivoted heat-indicator consisting of two bulbs and a connecting-tube containing volatile liquid, in combination with an adjusting-screw, said tube being provided with 115 a laterally-extending arm Z, arranged to come in contact with said screw, substantially as set forth.

In testimony whereof we affix our signatures in presence of two witnesses.
